UNITED STATES PATENT OFFICE.

HENRY GOLDWATER, OF ABERDEEN, WASHINGTON.

T-SQUARE.

1,045,695.

Specification of Letters Patent. Patented Nov. 26, 1912.

Application filed March 2, 1912. Serial No. 681,051.

To all whom it may concern:

Be it known that I, HENRY GOLDWATER, a citizen of the United States, residing at Aberdeen, in the county of Chehalis and State of Washington, have invented new and useful Improvements in T-squares, of which the following is a specification.

This invention relates to T-squares and the principal object of the invention is to provide a T-square having a laterally extending blade adjustably mounted thereon.

Further objects of this invention will appear as the following specific description is read in connection with the accompanying drawing, which forms a part of this application, and in which:

Figure 1 is a plan view. Fig. 2 is a transverse sectional view on the line 2—2 of Fig. 1. Fig. 3 is a similar section on the line 3—3 of Fig. 1. Fig. 4 is a detail longitudinal section on the line 4—4 of Fig. 1.

Referring more particularly to the drawing, 1 represents the head which has projecting therefrom a threaded stud 2 which is passed through the aperture 3 in the end of the blade 4. The blade 4 is held in adjusted position by means of the clamping nut 5 threaded upon the stud and engaged against a washer 6 which lies upon the top of the blade. The end of the blade is curved, as shown, and is provided with graduations 7 to coat with the graduations on the metal protractor 8 carried by the head 1 so as to determine the angular relation of the blade with the head. Dovetailed into the blade adjacent one edge and extending longitudinally of the blade is a scale 9 having suitable graduations thereon to adapt the device to any purpose. In the center of the blade there is formed a dove-tailed groove 10

in which a corresponding slide 11 is mounted. This slide carries a threaded stud 12 which is passed through an aperture 13 in the arm 14, the latter element being held clamped against the blade by means of the 45 nut 15 threaded on the stud and abutting the washer 16. This washer is adapted to rotate with the stud and is preferably provided with graduations to correspond with similar graduations on the arm 14. The 50 arm 14 is provided with a scale 17 dovetailed into its face adjacent one edge and is also provided with a dovetailed groove 18 in which a slide 19 is mounted. This slide carries a threaded stud 20 which is engaged by a 55 nut 21 adapted to hold a scale marker 22 in adjusted position. The scales are slidably mounted in the dovetailed grooves so that they can be removed whereby scales having 60 different forms of graduations may be supplied when necessary to accommodate the device for architects, engineers, draftsmen, or the like.

What is claimed is:

A T-square comprising a head, a blade pivoted thereon, a scale carried by the blade, an arm pivotally and slidably mounted upon the blade and adapted to operate over the scale, a slide dovetailed into said arm and movable longitudinally of the same, a scale 65 marker carried by the slide and adapted to move therewith at right angles to the arm, and means coacting with the slide for clamping the marker in adjustable position.

In testimony whereof I affix my signature 70 in presence of two witnesses.

HENRY GOLDWATER.
